UNITED STATES PATENT OFFICE.

HARRY FRIELAND, OF NEWARK, NEW JERSEY, ASSIGNOR TO VOGUE BRASSIERE MFG. CO., A CORPORATION OF NEW JERSEY.

COMBINATION ABDOMINAL SUPPORT AND BRASSIERE.

Application filed May 22, 1924. Serial No. 715,094.

This invention relates, generally to improvements in women's under-garments; and, the present invention has reference, more particularly, to a novel and simply-constructed garment in the form of a combined brassière and abdominal support, with a view of providing a comfortable garment which when worn about the body, serves to flatten the stomach and at the same time has the usual brassière-effect, in adapting itself perfectly to the lines or contour of the breasts of the wearer.

The present invention, therefore, has for its principal object to provide a simple, neat, and efficient garment in the form of a combined brassière and abdominal support, of the general character hereinafter more fully set forth, and for the purposes herein-above stated.

Other objects of the present invention not at this time more particularly enumerated will be clearly understood from the following detailed description of the present invention.

With the various objects of the present invention in view, the said invention consists, primarily, in the garment, made in the form of a combined brassière and abdominal support, and hereinafter more fully set forth; and, the invention consists, furthermore, in the novel arrangements and combinations of the several elements and parts employed in the construction of the garment, as well as in the details of the construction of the said parts, all of which will be more fully described in the following specification, and then finally embodied in the clauses of the claims, which are appended to and which form an essential part of the said specification.

The invention is clearly illustrated in the accompanying drawings, in which:

Figure 1 is a pictorial representation of the combination garment embodying the principles of the present invention, looking toward one side and the rear of the garment, and showing the same in its position upon the body of the wearer. Figure 2 is a similar view of the garment upon the body of the wearer, showing more particularly the front of the garment; and Figure 3 is a similar view of the garment, shown in its position upon the body of the wearer, but illustrating the brassière portion of the garment in sectional representation and opened out so

as to show more particularly the general arrangement of the abdominal supporting portion or element of the garment.

Figure 4 is a view of the garment, spread out, so as to show the inner surface portions of the same, a part of the garment being represented in section or broken away, to illustrate an arrangement of stays employed in the construction of the garment; and Figure 5 is a perspective view of the opened garment, with portions of the same being represented in section, and looking toward the interior of the garment.

Figures 6 and 7 are diagrammatic representations of the garment, illustrating the relative positions of the brassière-portion to the abdominal supporting element, Figure 6 showing the positions before wearing, and Figure 7 illustrating the positions when disposed about the body of the wearer.

Figure 8 is a perspective view of a slightly modified construction of combination garment, but still embodying the principles of the present invention.

Similar characters of reference are employed in all of the said above described views, to indicate corresponding parts.

Referring now to the said drawings, the reference-character 1 indicates a complete garment in the form of combined brassière 80 and abdominal support 3, made according to and embodying the principles of the present invention, the abdominal supporting member or element 3 comprising the members 4 and 5 of any suitable material, their vertical marginal edge-portions 6 and 7 being suitably connected by overlapping seams or folds 8, and stitching 9 to an insert 10 of a flexible material, as elastic webbing. Along their upper edges and their lower 95 edges, the said members 4 and 5 are respectively provided with suitable overlapping seams, folds, or tape, as 11 and 12, suitably stitched, as indicated by the reference-character 13. Other members 14 and 15, are secured to the respective members 4 and 5 by means of overlapping seams or folds 16 and 17, suitably attached, as at 18, the said members 14 and 15 being of greater length than the members 4 and 5 and the insert 10, so 100 as to provide above said members 4 and 5 and the insert 10 and intermediate the upper portions of the members 14 and 15 a suitable bust-receiving space substantially as 105 shown in the several figures of the drawings, 110

with the brassière section 2 connected to and between said members 14 and 15 to extend over said bust-receiving space, all as and for the purpose to be presently more fully described. At their upper and lower marginal edges, the said members 14 and 15 may be provided with the respective overlapping seams, folds, or tape, 19 and 20, and the stitching 21. The reference-characters 22 and 23 indicate other members also provided with overlapping seams or folds, as 24 and 25, and stitching 26, the upper portions of said seams or folds 24 and 25 being respectively secured to marginal overlapping seams or folds 27 and 28, and stitching 29 with which the members 14 and 15 may be provided, the various parts being arranged to provide triangular spaces for attachment of the flexible hip-gussets or inserts 30 and 31, usually made from elastic webbing. At their upper and lower edges, the said members 22 and 23 are made with suitable overlapping seams, folds, or tape, as 32 and 33, and stitching 34, and at their longitudinal edges the said members 22 and 23 are made with other overlapping seams, folds, or tape, as 35 and 36, and stitching 37, the said seams, folds or tape 35 and 36, being provided with suitably spaced garment fasteners 38 of any desirable construction, or other usual fastening means, as will be evident. Upon its inner face, the previously mentioned insert 10 may be provided with a series of pockets, as 39, in which are arranged and suitably secured reinforcing stays 40, of suitable material, the said stays being preferably made short and of such length, that the lower portion of the insert will flex to the conformation of the stomach of the wearer, without causing distress or discomfort.

As shown, the previously mentioned brassière-member or element 2 is also preferably provided at its upper and lower marginal edges with overlapping seams, folds, or tape, as 41 and 42, and stitching 43, and at its side-edges with overlapping seams or folds 44 and stitching 45, the lower part of the brassière-member or element having a certain fullness and overlapping a portion of the upper part of the insert 10, but as is shown in the several figures of the drawings, being not fastened to the said insert 10. Gussets 46 of elastic webbing may also be inserted at the sides of the said brassière-member or element 2 and the members 14 and 15, the upper parts of the side-edges of the member or element 2 being permanently secured to the members 14 and 15 by the seams or folds 16 and 17 and the stitching 18, substantially as shown. The upper marginal edges of the brassière-member or element and of the various members 14, 15, 22 and 23, as will be seen more particularly from an inspection of Figure 4 of the drawings, are in alignment with each other, and the over-

lapping folds or bindings 32, 19 and 41 of the various members may be made in one continuous piece. Furthermore, as has been stated, the lower part of the brassière-member or element 2 overlaps a portion of the abdominal supporting member 3, the said member or element 2 being of such fullness, so that a considerable open space is provided between the said overlapping space, when the garment is not being worn, but which open space practically becomes closed, as soon as the garment is placed and secured about the body of the wearer, thus producing a continuous and graceful body-effect when worn, the abdominal supporting member 3 sufficiently pressing against the stomach of the person, so as to flatten the stomach, and the fullness of the brassière-member or element 2, conforming itself directly to the curvature of the busts, and comfortably supporting the same, as will be clearly evident from an inspection of Figure 2 of the drawings.

Shoulder-straps, as 47, and hose-supporting means, as 48, may be employed with the combination, as shown.

In lieu of providing the garment at its back with fastening means, as herein-above described, the garment may be separable at the side, being provided with suitable fasteners, as 49, and as represented in the modification shown in Figure 8 of the drawings.

Of course, I am aware that some changes may be made in the general arrangements and combinations of the various elements comprising the combination garment, as well as in the details of the construction of the several parts thereof, without departing from the scope of the present invention as set forth in the foregoing specification, and as defined in the clauses of the claims which are appended thereto. Hence, I do not limit my present invention to the exact arrangements and combinations of the said element, nor do I limit myself to the exact details of the construction of the various parts, as described in the said specification, and as illustrated in the accompanying drawings.

I claim:

1. A combination garment of the kind described, comprising side and back panels in fixed united relation, an abdominal support in fixed united relation to and between the lower portions of the forward edges of said side panels, said support including intermediate the side portions a longitudinally disposed elastic member, the upper portion of said elastic member having substantially vertically disposed laterally spaced reinforcing stays incorporated therewith, an independent bust enclosing and supporting member in fixed united relation to and between the upper portions of the forward edges of said side panels, and said latter member possessing an excess fulness as compared with said abdominal support and be-

ing arranged with its lower portion in exterior overlapping relation to said abdominal support.

2. A combination garment of the kind described, comprising side and back panels in fixed united relation, an abdominal support in fixed united relation to and between the lower portions of the forward edges of said side panels, said support including intermediate the side portions a longitudinally disposed elastic member, the upper portion of said elastic member having substantially vertically disposed laterally spaced reinforcing stays incorporated therewith, an independent bust enclosing and supporting member

in fixed united relation to and between the upper portions of the forward edges of said side panels, said latter member possessing an excess fulness as compared with said abdominal support and being arranged with its lower portion in exterior overlapping relation to said abdominal support, and said overlapping lower portion of said bust enclosing and supporting member having elastic gore members at each side thereof.

In testimony, that I claim the invention set forth above I have hereunto set my hand this 20th day of May, 1924.

HARRY FRIELAND.
